UNITED STATES, PATENT OFFICE.

FRANK F. FISCH, OF THE DALLES, OREGON.

PORTABLE FIREPROOF BUILDING.

Application filed April 4, 1923. Serial No. 629,886.

This invention relates to metallic structures, and particularly to relatively small portable metallic buildings.

One of the objects of this invention is to provide a building of this character which does not require studding for its support nor any vertical columns or beams but which is so constructed that the roof is supported entirely by the compound metallic sheet 10 which is used for the side walls of the building.

A further object is to provide a building of this character in which the parts may be readily assembled or disassembled whenever desired and which, therefore, is particularly suitable for portable houses for use by campers, tourists and wherever portable buildings are desired.

A still further object is to provide a building of this character in which the walls and roof are formed of two sheets of material, one of said sheets being corrugated and with an interposed layer of fire-proof material between the sheets.

Another object is to provide a device of this character in which one of the sheets forming the compound wall is bent so as to particularly strengthen the wall and render it rigid.

Other objects have to do with the details of construction and arrangement of parts as will appear more fully hereinafter.

My invention is illustrated in the accompanying drawings, wherein:—

Figure 1 is a perspective sectional view of a building constructed in accordance with my invention, the parts being broken away;

Figure 2 is an end elevation of the building shown in Figure 1;

Figure 3 is a section on the line 3—3 of Figure 1;

Figure 4 is a section on the line 4—4 of Figure 2;

Figure 5 is a section on the line 5—5 of Figure 2;

Figure 6 is a section on the line 6—6 of Figure 1;

Figure 7 is a fragmentary transverse section through the roof but showing a modified form of crown or capping;

Figure 8 is a fragmentary perspective view of one edge of one of the siding plates.

Referring to these drawings, it will be seen that I have illustrated a rectangular

building having a gable roof, though I do not wish to be limited to this particular shape. This building is formed of wall sections, as clearly illustrated in section in Figure 6 and designated A. As illustrated, there are two of these wall sections on each long side of the building and one wall section B at each end of the building. The wall sections A each consist of an inner and outer layer or thickness of sheet metal, designated 10 and 11, the outer layer being 65 corrugated vertically and being formed of one or more lengths of material, through preferably one length of material is to be used. If more than one length of material is used, the margins of the material are 70 overlapped and one sheet fastened to the other.

Disposed within the vertically corrugated sheet 10 is a plain sheet of material 11. This sheet at its lower end is inwardly bent, 75 as at 12, then outwardly bent, as at 13, and then downwardly bent, as at 14. The flange thus formed is adapted to rest upon the sills D, which in turn supports the floor board C. The upper margin of the inner sheet 11 is outwardly flanged, at as 15, then inwardly bent, at at 16, against the flange 15 and then downwardly bent, as at 17. The outer sheet 10 extends below the flange at the lower edge 14 of the inner sheet 11 and these inner and outer sheets may be held together in any suitable manner as, for instance, by rivets passing through the two sheets, the rounded or smooth heads of the rivets being on the inside face of the wall. 90

Disposed between the outer sheet 10 and the inner sheet 11 is a layer or sheet 18 of fire-proof material such as sheet asbestos. I do not wish to be limited, however, to the use of asbestos, as other fire-proof materials 95 may be disposed in a layer between these two sheets 10 and 11 and it is within my invention to use any fire-proofing layer which I may desire to use.

As will be seen from Figure 8, one end 100 of the sheet 10 is angularly bent, as at 19, and the flange 17 at its end extends over the sheet 10 and is angularly bent, as at 20, so as to reinforce this flange 19. The gable ends B of the structure are of the same 105 character as the sides A, that is formed with an outer vertically corrugated sheet and an inner plain sheet held together by bolts and

having an intermediate layer of fire-proof material. The roof sections are also formed of an inner sheet 21 which is plain or flat and an outer sheet 22 which is corrugated in a direction from the ridge of the roof to the eaves thereof, and disposed between these two sheets is the intermediate layer 23 of fire-proof material, such as asbestos, previously referred to.

- 10 This roof is composed of sections, the sections meeting at the ridge of the roof and extending beyond the walls A and B. The inner sheet 21 of each roof section has at its inner edge an upwardly extending flange 24.
- 15 This flange is bent downwardly upon itself, as at 25, and then extends downward along the upper face of the sheet 21 so as to reinforce this upwardly extending flange and make it of double thickness (see Fig. 2).
- 20 The lower edge of this inner sheet is folded back upon itself, as at 26, and the corrugated sheet 22 rests upon the upper face of this return reinforced portion 26 and also extends over the returned portion 25. The
- 25 end of the roof section which projects beyond the gable is also turned back upon itself or reinforced, as at 27. The roof sections are adapted to be held to the wall sections by bolts 28 which extend downward
- 30 through the roof sections and through the projecting flanges 15 of the wall sections. The inner edges of the roof sections, as before remarked, are bent so as to form a flange 24 and a crest 29 is adapted to be used therewith, this crest being made of sheet metal bent into an arrow shape or triangular form in cross section and having a downwardly extending supporting web 30 disposed between the flanges 25 and
- 40 bolted at intervals thereto.

I do not wish to be limited to this, as it is obvious that, as illustrated in Figure 7, a longitudinally extending plate or strip 31 might be disposed between these flanges

- 45 24 and be bolted thereto. This strip of bar is preferably of steel $2\frac{1}{2} \times \frac{3}{8}$ or may be of any suitable length and permits the use of an ordinary ridge capping 32 whose skirts are corrugated and extend over onto the
- 50 corrugated upper face 22 of the roof. Any suitable crest or rigid piece may be used in connection with this roof and supported by the flanges 24.

As illustrated in Figure 1, I have formed the building in two parts with intermediate walls E. These intermediate walls do not have a corrugated facing but are flat walls which are disposed against each other and between these intermediate walls E is a

60 layer of fire-proof material 33. Bolts pass through these two abutting walls and detachably hold these walls in engagement with each other. These walls are of the same shape as the gable walls B but are

65 notched, as at 34, for the passage of the web

30 or the bar 31 of the rigid piece or crest. Both of these walls E are flanged at their lower ends, as at 35, these flanges corresponding to the flanges 12 on the side and end walls.

If a building formed in two sections is used, then the roof is preferably formed in two sections also, that is the inner edges of the sheet 21 are upwardly turned or angled, as at 36, and bolted together by bolts 37, and cap pieces 38 being also bolted to these flanges and extending down over the abutting faces of the flanges so as to prevent rain from passing down between these abutting faces. Where the structure is made in two sections, the outer corrugated sheet 10 of one section will preferably overlap the corrugated sheet of the other section. Of course, suitable doors and windows will be formed in the building in an obvious manner.

A building constructed as described does not require studding or other framing for its support, as the building is supported by the vertically corrugated sheets 10 of the side walls, which I find will resist considerable downward pressure when braced and held in place by the roof sections. The flanges 12 may be perforated at intervals for the passage of nails, screws or bolts whereby the structure may be held down to the sills D or the flooring board C. The roof sections extend beyond the side and end sections of the structure so as to completely shed water. The structure may be readily put up and because of the fact that it is built in sections may be readily handled and shipped. I design to build the structure in units, each unit being 10 x 12, and join two units up to make a larger building. These structures may be used as garages, campers' cabins, and for any purpose for which a portable house is necessary or desirable.

I claim:—

1. A portable house, the walls of which are formed of side and end sections, each section consisting of an inner flat sheet of metal and an outer vertically corrugated sheet of metal, the sheets being bolted to each other, the inner sheets of the sections forming the side and end walls having at their upper ends outwardly projecting flanges extending downward over the top edges of the upper sheet, to afford a support for a roof.

2. In a metallic building, a wall section composed of an outer sheet of vertically corrugated metal and an inner sheet of flat metal, the inner sheet at its upper ends being outwardly flanged over the top of the outer sheet and then returned upon itself and extending downward between the inner and outer sheets, to thereby afford a support for a roof.

3. A portable metallic building of the character described including two units, each

- unit having opposite side walls and end walls, one of said end walls and both side walls having outwardly projecting flanges at their upper ends, whereby to support a roof, the two units of which the building is composed having the remaining end walls abutted against each other, and means joining said end walls.
4. In a metallic building formed of sections, each section including a flat inner sheet of metal and an outer vertically corrugated sheet, the outer sheet extending below the inner sheet and the inner sheet having its lower end inwardly flanged whereby the outer corrugated sheet may extend down over the sill of a sub-structure and the flange may rest upon the sill thereof.
5. In a metallic building, a wall section composed of inner and outer sheets of metal, the outer sheet extending below the inner sheet to form a skirt and the inner sheet being inwardly flanged at its lower edge, said inner sheet at its upper end being outwardly flanged over the top of the outer sheet to provide a roof-supporting means and the sheets being engaged with each other.

In testimony whereof I hereunto affix my signature.

FRANK F. FISCH.
